(57) **CLAIM**

The ornamental design for an ipod docking station as shown.

DESCRIPTION

FIG. 1 is a top front and side perspective view of an ipod docking station showing my new design;

FIG. 2 is a top front and side perspective view thereof in its closed position;

FIG. 3 is a front elevational view thereof;

FIG. 4 is a front elevational view thereof in its closed position;

FIG. 5 is a top rear and side perspective view thereof;

FIG. 6 is a top rear and side perspective view thereof in its closed position;

FIG. 7 is a rear elevational view thereof;

FIG. 8 is a rear elevational view thereof in its closed position;

FIG. 9 is a left side elevational view thereof;

FIG. 10 is a left side elevational view thereof in its closed position;

FIG. 11 is a right side elevational view thereof;

FIG. 12 is a right side elevational view thereof in its closed position;

FIG. 13 is a top view, the bottom being a mirror image thereof; and,

FIG. 14 is a top view in its closed position, the bottom being a mirror image thereof.

The broken line portions of the ipod docking station of FIG. 1 and FIG. 3 are environmental only and form no part of the claimed design.
